United States Patent Office

Des. 186,192
Patented Sept. 22, 1959

186,192

ORGAN CONSOLE

William Millington, Grand Rapids, Mich., and Wilbur M. Day, Kenwood, Ohio, assignors to The Baldwin Piano Company, Cincinnati, Ohio, a corporation of Ohio

Application January 27, 1958, Serial No. 49,407

Term of patent 14 years

(Cl. D56—9)

FIG. 1.

FIG. 2.

Fig. 1 is a perspective view of an organ console showing our new design.

Fig. 2 is a partial end elevation showing certain elements of the upper part of the console in section.

We claim:

The ornamental design for an organ console, substantially as shown.
